CLAIM

I claim the ornamental design for a thimble for needle work, as shown and described.

DESCRIPTION

FIG. 1 is a perspective view of a thimble for needle work according to my design;

FIG. 2 is a front view thereof;

FIG. 3 is a top view thereof;

FIG. 4 is a bottom view thereof;

FIG. 5 is a rear view thereof;

FIG. 6 is a cross sectional view thereof, taken at line 6—6 in FIG. 2; and,

FIG. 7 is a perspective view thereof showing the thimble in the condition of use.

The broken lines in FIG. 7 represent environmental subject matter and form no part of the claimed design.
